UNITED STATES PATENT OFFICE.

ALDEN L. PUTNAM, OF DETROIT, MICHIGAN, ASSIGNOR TO DETROIT PRESSED STEEL COMPANY, OF DETROIT, MICHIGAN, A CORPORATION OF MICHIGAN.

MACHINE FOR ROLLING WHEEL-BLANKS.

1,208,831.

Specification of Letters Patent. Patented Dec. 19, 1916.

Application filed February 14, 1916. Serial No. 78,162.

To all whom it may concern:

Be it known that I, ALDEN L. PUTNAM, a citizen of the United States of America, residing at Detroit, in the county of Wayne 5 and State of Michigan, have invented certain new and useful Improvements in Machines for Rolling Wheel-Blanks, of which the following is a specification, reference being had therein to the accompanying drawings.

The invention relates to the manufacture of sheet-metal blanks having a cross section of varying thickness and designed for the manufacture of pressed sheet metal wheels. 15 It is the object of the invention to provide means for rolling a blank of uniform gage to convert the same to the desired variation in gage, and to this end the invention comprises the construction as hereinafter set forth.

In the drawings: Figure 1 is a vertical central section partially in elevation; Fig. 2 is a section on line 2—2 Fig. 1; Fig. 3 shows the manner of engaging the blank; and Fig. 25 4 is a section of the completed blank.

In the process of forming the blanks an original blank cut from sheet-metal of a uniform gage and the maximum thickness is rolled to thin certain portions thereof and to 30 also enlarge the diameter. My improved machine performs this operation expeditiously through the coöperation of pairs of conical rolls arranged on opposite sides of the blank with their axes radiating from the center 35 thereof.

As shown, A is a suitable frame, on which is mounted a pivot bearing B for engaging the center of the blank, which latter is preferably cupped as indicated at C for engagement 40 with said pivot, and D is a conical roll below the blank and mounted upon a supporting shaft E which engages a journal bearing F in the frame.

G is an end-thrust bearing for the shaft E 45 beyond the bearing F, and H is a bevel gear-wheel mounted on the shaft and engaging a bevel pinion I on a drive-shaft J.

K is a conical roll above the blank, which is similarly mounted on a shaft L in a journal bearing M, having an end-thrust bearing N and a bevel gear-wheel O in mesh 50 with the bevel pinion P on the shaft J. The upper shaft L is, however, longitudinally adjustable and to this end the bearing N 55 slidably engages guideways Q in the frame,

while the gear-wheel O has a spline engagement R with the shank L' of the shaft L. This permits of the longitudinal adjustment of the shaft L without interfering with its rotative drive.

For adjusting the shaft L longitudinally, a suitable operating mechanism is provided, such as a hand-wheel S operating through a gear-train T to actuate pinions U engaging racks V on opposite sides of the bearing M. 60 The arrangement is such that by rotating this hand-wheel, the bearing M and shaft L are adjusted longitudinally so as to withdraw the roll K from the roll D and permit of engagement of the blank between said 70 rolls.

For holding the blank in engagement with the pivot bearing B a vertically-adjustable clamp W is arranged in alinement with said bearing. This clamp is raised or lowered by a threaded shaft W' engaging a correspondingly threaded bearing in the frame and operated by a hand-wheel W'. An anti-friction ball or roller thrust bearing W² is preferably placed between the shaft W' and 80 clamp W and a similar anti-friction thrust bearing X is arranged between the pivot B and its supporting bearing B'.

With the construction as described in operation the blank to be rolled which has been 85 previously centrally cupped for engagement with the pivot B, is heated and placed on said pivot while the roll K is withdrawn. The hand-wheel S is then operated to lower the roll K, and rotary motion is simultaneously imparted to both the rolls K and D through the mechanism described. This will roll the blank concentric to its axis so as to reduce the thickness of the portion in contact with the rolls and to enlarge the diameter. 90 Disengagement of the blank during this operation is prevented by the clamp W, which holds the cupped portion down upon the pivot bearing B, while the anti-friction 95 end-thrust bearings W² and X permit of free rotation. When the blank is sufficiently thinned the roll K is again withdrawn, the clamp W released and the blank disengaged and another blank inserted.

Instead of a single pair of rolls I preferably have at least two pair with differently fashioned contours. Thus, as shown, the rolls K' and D' on the left correspond to the rolls K and D on the right with the exception of a change in contour. This as 110

specifically shown consists of tapering portions Y and Y' at opposite ends of the central portion Y² so as to produce a gradual change in ~~in~~ section of the blank from the periphery and the hub to a thin portion intermediate the same. The thickness of the periphery of the blank is also thinner than the thickness of the hub, but this operation is performed by the rolls K and D. The rolls K' and D' may be driven by suitable mechanism similar to that used in connection with the rolls K and D.

What I claim as my invention is:—

1. The combination with a pair of conical driven rolls, of means for revolvably supporting a blank with its axis of rotation passing through the point of intersection of the axes of said rolls, and a common means for adjusting one of said rolls axially toward or from the coöperating roll.
2. The combination with a pair of conical driven rolls relatively adjustable toward or from each other with their axes intersecting in a fixed point, a clamp for supporting a blank between said rolls, and a revoluble support for said clamp having its axis of rotation intersecting the point of intersection of the axes of said rolls.
3. The combination with a pair of conical driven rolls, of a revoluble work-support having its axis of rotation intersecting the axes of said rolls in a fixed point, said work-

support being adapted to engage a cupped hub member on the blank to hold the latter between said rolls, a clamp for holding said blank upon said revoluble support, and anti-friction bearings for said support and clamp to permit the free rotation of said blank.

4. The combination with a pair of conical driven rolls, of supporting shafts therefor extending from the large ends thereof, bearings for said shafts, a frame on which said bearings are mounted, guides for the bearings of one of said shafts permitting adjustment thereof longitudinally of the shaft, members oppositely projecting from said adjustable member, and means acting through both of said members for adjusting the bearing longitudinally.

5. The combination with two pairs of conical rolls, of a non-adjustable pivot disposed between corresponding members of said pairs, said members being likewise non-adjustable, a coöperating pivot adjustable to or from the first-mentioned pivot and disposed between the other two rolls of said pairs, the rolls at each side of the adjustable pivot member being adjustable to or from their fellows and being formed to act differentially upon substantially the same portion of a blank.

In testimony whereof I affix my signature.

ALDEN L. PUTNAM.
